UNITED STATES PATENT OFFICE

FRANK C. PICKARD, OF ERIE, PENNSYLVANIA, ASSIGNOR TO THE STANDARD STOKER COMPANY, INCORPORATED, A CORPORATION OF DELAWARE

FUEL DISTRIBUTOR

Application filed October 3, 1930. Serial No. 486,081.

The present invention relates to fuel distributing means, for use in connection with mechanical stokers.

It is an object of the invention to provide fuel distributing means arranged to spread fuel uniformly and evenly and with a substantially equal classification of coarse and fine fuel over the entire firebed area of a firebox.

10 It is a further object of the invention to provide a distributor plate, in a distributing means of the character described, that is simple in construction, functions efficiently and is cheap to manufacture.

15 It is a further object of the invention to provide a distributor plate, in fuel distributing means of the character described having a novel configuration and design.

20 Other objects and advantages of the invention will be apparent during the course of the following description, and from the claims and drawings, in which

25 Fig. 1 is a central longitudinal section of a portion of a locomotive with a stoker therefor showing the invention in place;

Fig. 2 is a plan view of Fig. 1;

30 Fig. 3 is an end view taken from within the firebox through the firing opening showing the novel distributor plate;

Fig. 4 is a vertical cross section on the line 35 4-4 of Fig. 2; and

Fig. 5 is an isometric view of the novel distributor plate.

For purpose of illustration my invention 40 is shown as applied to a locomotive stoker, though it will become apparent as the description proceeds that its application is not necessarily so restricted but may be used equally as well with other types of stokers.

A portion of a locomotive is designated generally at 10; at 11 its boiler firebox provided with grates 12, and a backhead 13 with a firing opening 14 therein.

Fuel is delivered to the locomotive from 45 a tender, not shown, by suitable stoker mechanism, only so much being illustrated and described as is essential to a complete understanding of the invention. The forward tubular conduit section or riser of a flexible conduit system of the stoker is designated as

15 and extends to the firing opening 14 of the boiler. The riser 15 is carried from the backhead 13 by a supporting bracket 16 and terminates at its lower end in a spherical seat 17 receiving the ball member 18 of a conduit section 19 leading forwardly from a source of fuel supply.

55 From its lower end the riser 15 extends upwardly and forwardly, flaring outwardly at its upper end, and communicates with the

50 firing opening 14 through its laterally spreading and substantially horizontal mouth portion 20. The mouth portion 20 is provided with the flanges 21 for attachment to the backhead by suitable fastening means, as by bolts, not shown. This mouth portion is formed with an upstanding wall 22 to which is detachably connected the novel distributor plate indicated as a whole at 23, which forms an extended floor portion of the riser and extends through the firing opening into the firebox. Rearwardly of the plate 23 and outside of the firebox is a vertically disposed

60 nozzle or distributor head 24 to which pressure fluid such as steam is supplied by a desired number of supply pipes 25. The distributor head 24 is provided with openings or jets in horizontal alignment for emitting a fan shaped blast of fluid across the distributor plate 23. The jets 26 are positioned

65 a predetermined distance above the rear of the distributor plate as will be hereinafter described. The riser conduit 15 is provided with a removable cover section 27 which may be hinged at its upper end and held in closed

70 position by a latch 28, whereby access may be had to the interior of the riser conduit.

75 The distributor plate 23 is formed of a unitary casting and its top surface is so configured and designed as to permit uniform distribution of fine and coarse fuel over all parts of the firebed area.

80 The central longitudinal portion of the plate 23 slopes upwardly from rear to front forming the inclined plate member 29 which affords a longer trajectory for the fuel swept thereover. The inclined plate member 29 is provided with a crown 30 extending along the longitudinal center line thereof and on either side of the crown 30 the top surface

of the inclined plate member slopes gently downward forming the sloping faces 31 and 32. At the forward central portion of the inclined plate member 29 and superimposed upon the crown 30 is an upstanding V-shaped block 33 designed to deflect a portion of the fuel that would normally be delivered to the front of the fire box and spread it over the sides and front corners of the firebox. The front corners 34 and 35 of the inclined plate member 29 are slanted upwardly towards the front corners of the firebox and form with the downwardly sloping faces 31 and 32 the rearwardly diverging channels 36 and 37.

On each side of the inclined plate member 29, there are formed in the plate depressions or pockets 38 and 39 sloping downwardly from rear to front and merging rearwardly into the surface of the inclined plate member 29. The forward ends of the pockets 38 and 39 are arcuate in form curving laterally to the sides of the plate and forming with the plate the forwardly and laterally curved walls 40 and 41. A portion of the fuel is intercepted by the pockets 38 and 39 and is deflected to the rear corners of the firebox by the laterally curving walls 40 and 41.

It will be observed that the jet openings 26 are disposed at a height above the rear of the plate 23 so that the center and zone of highest intensity of the blast strikes the large lumps of fuel that are deposited about the crown 30 of the inclined plate member 29 approximately in line with their center of gravity whereby they are given a maximum impetus and carried to the furthermost areas of the firebed. The lumps of fuel deposited on the sloping faces 31 and 32 of the plate member 29 on either side of the crown 30 will be struck by the blast at point above their center of gravity and will therefore, not be given as great an impetus and will not be carried into the firebox as great a distance. Thus the farther to the sides that the fuel is deposited on the sloping faces 31 and 32 the less will be its impetus and by such a graduation, lump fuel is distributed uniformly and evenly over the entire firebed area. The lower pressure zone or outer periphery portion of the blast will strike the finer particles of fuel which do not require as great a projectile force as the large lumps of fuel to reach the forward portion of the firebox.

In operation fuel is delivered through the riser conduit 15 over the distributor head 24 onto the novel distributor plate 23 into the zone of action of the single pressure fluid blast issuing from the jet openings 26 of the distributor head. The greater portion of the fuel is projected forwardly across the inclined plate member 29 and other portions are intercepted by the pockets 38 and 39 and deflected to the rear corners of the firebox by the laterally curving walls 40 and 41. A portion of the fuel deposited about the crown

30 of the plate member 29 is projected forwardly over the V-shaped block 33 and feeds the central and forward areas of the firebed, and the remainder is deflected by the V-shaped block across the upwardly slanting corners 34 and 35 of the plate member 29 which provide a longer trajectory for the fuel, thereby permitting it to reach the front corners and sides of the firebox. Other portions of fuel are projected into the firebox over the sloping faces 31 and 32 on either side of the V-shaped block, with a graduated impetus as hereinbefore explained and spread fuel over the intermediate and rearward portions of the firebed.

It will be evident that I have provided a novel fuel distributing means that is very simple in construction, is cheap to manufacture, and functions efficiently to distribute fine and lump fuel evenly and uniformly over all parts of the firebed area.

I claim:

1. A fuel distributor plate for stokers comprising an upwardly inclined section extending longitudinally forward through the central portion of said plate, an upstanding V-shaped deflecting abutment at the forward central portion of said inclined section, and lateral deflecting means formed with said plate on either side of said inclined section.

2. A fuel distributor plate for stokers comprising an upwardly inclined section extending longitudinally forward through the central portion of said plate, a crown extending longitudinally along the center line thereof, the top surface of said inclined section sloping downwardly from either side of said crown, and an upstanding V-shaped block at the forward central portion of said inclined section.

3. A fuel distributor plate for stoking mechanism comprising an upwardly inclined central section, the top surface thereof having a crown extending longitudinally along its center line and sloping downwardly on either side from said crown, an upstanding fuel deflecting abutment superimposed on said crown at the forward central portion of said inclined central section and pockets in said plate on either side of said inclined central section having forwardly and laterally curving walls.

4. A fuel distributor plate for stoking mechanism comprising an upwardly inclined central section, the top surface thereof having a crown extending longitudinally along its center line and sloping downwardly on either side from said crown, and the forward corners thereof inclined upwardly forming rearwardly diverging channels with said downwardly sloping surface, an upstanding V-shaped block on the forward central portion of said inclined section, and pockets in said plate on either side of said inclined cen-

tral section having forwardly and laterally curving walls.

5. As a new article of manufacture an integral cast metal distributor plate comprising a central inclined section, an upstanding V-shaped block at the forward central portion thereof and a crown extending longitudinally along the center line thereof, said inclined central section sloping downwardly 10 from either side of said crown and inclined upwardly at its forward corners, and pockets in said plate on either side of said inclined central section having forwardly and laterally curving walls.

15 6. In a fuel distributing system, in combination, a distributor plate, a distributor head rearward of said plate, said plate comprising a forwardly extending and upwardly inclined section having a fuel deflecting abutment at its forward central portion, a crown extending longitudinally along its center line and upwardly inclined forward corners, and a plurality of jet openings spaced in horizontal alignment in the front face of said 20 25 distributor head arranged a height above the rearward top surface of said plate so that the center of the blast issuing from said openings impinges against said inclined section intermediate its forward and rearward edge.

30 7. In a fuel distributing system in combination, a distributor plate, a distributor head rearwardly of said plate, and means for delivering fuel onto said plate, said plate comprising a central inclined section having a crown extending longitudinally along its center line and top faces sloping downwardly from either side of said crown, a plurality of horizontally aligned jets in said distributor 35 40 head arranged a height above the rearward top surface of said plate so that the center of the blast issuing from said jets strikes the lump fuel delivered about the crown of said inclined section substantially in line with its center of gravity and the fuel delivered to the sloping faces at progressively higher points whereby fuel is projected with progressively lesser degrees of force.

45 In testimony whereof I affix my signature.
50 F. C. PICKARD.
